UNITED STATES PATENT OFFICE

101,379

DESIGN FOR A GOBLET OR SIMILAR ARTICLE

John D. McKee, Chicago, Ill., assignor to The Pope-Gosser China Co., Coshocton, Ohio, a corporation of Ohio

Application July 23, 1936, Serial No. 64,009

Term of patent 3½ years

To all whom it may concern:

Be it known that I, John D. McKee, a citizen of the United States, residing at Chicago, in the county of Cook and State of Illinois, have invented a new, original, and ornamental Design for a Goblet or Similar Article, of which the following is a specification, reference being had to the accompanying drawing, forming part thereof.

The figure is a perspective view of a goblet, showing my new design, the ornamentation being continued around the entire goblet.

I claim:

The ornamental design for a goblet or similar article, as shown and described.

JOHN D. MCKEE.
